UNITED STATES PATENT OFFICE.

HENRY E. BOSTWICK, OF NEW MILFORD, CONNECTICUT.

DESIGN FOR BUTTONS.

Specification forming part of Design No. **7,891**, dated November 24, 1874; application filed September 23, 1874.
[Term of Patent 7 years.]

CASE A.

To all whom it may concern:

Be it known that I, HENRY E. BOSTWICK, of New Milford, in the county of Litchfield and State of Connecticut, have invented a Design for Buttons, of which the following is a specification:

The nature of my design is fully represented in the accompanying photographic illustration, to which attention is directed.

My invention consists of a simple stripe, bar, or band, the same being mottled in spots, and passing across the entire face of the button through the central part thereof.

I do not consider any particular color or shade of the stripe, bar, or band, or of the remaining portions of the face of the button, to be an essential element of my design; but only that a segment of the face of the button passing through the central part thereof shall be so dyed, colored, or painted in relation to the remaining segments, or the remaining segments shall be so dyed, colored, or painted in relation to the central segment that, by the contrast of the colors used, the central segment shall become a stripe, bar, or band

extending across the entire face of the button, and that such stripe, bar, or band, whatever may be the prevailing or foundation color, shall be mottled in spots.

The stripe, bar, or band passing through the central part of the face of the button is not limited to any special width, neither is the contour of the button nor the surface of the face thereof limited to any special shape or form.

The button may have one or more metallic center pieces, used simply as ornaments or to re-enforce the eyelet hole or holes of the same.

What I claim is—

A design for a button, consisting of a single stripe, bar, or band, such stripe, bar, or band being mottled in spots, and extending across the entire face of the button through the central part of the same, substantially in the manner above described.

HENRY E. BOSTWICK.
